UNITED STATES PATENT OFFICE.

SIDNEY C. VENNERS, OF NEW YORK, N. Y.

SIGNAL SYSTEM.

1,115,349.

Specification of Letters Patent. Patented Oct. 27, 1914.

Application filed April 17, 1914. Serial No. 832,585.

To all whom it may concern:

Be it known that I, SIDNEY C. VENNERS, a citizen of the United States, residing at New York, in the county of New York and State of New York, have invented new and useful Improvements in Signal Systems, of which the following is a specification.

This invention relates to improvements in signal systems and has particular application to a combination burglar and fire alarm system.

In carrying out the present invention, it is my purpose to provide a burglar and fire alarm system which may be used in conjunction with telephone lines and wherein the telephone line will be opened upon the sounding of the fire alarm or the burglar alarm so that the operator at the central office may hear the alarm and act accordingly.

It is also my purpose to provide a system of the class described which will embrace the desired features of simplicity, efficiency and durability, which may be installed and maintained at a minimum expense and which will operate effectively for its intended purposes.

With the above and other objects in view, the invention consists in the construction, combination and arrangement of parts hereinafter set forth in and falling within the scope of the claim.

In the accompanying drawings: Figure 1 is a diagrammatic view of a signal system constructed in accordance with the present invention. Fig. 2 is a view in elevation of the relay. Fig. 3 is a top plan view of the relay. Fig. 4 is a view in elevation of the manually operated switch.

Referring now to the drawings in detail, 1 designates a telephone transmission line including the usual set of subscribers' instruments 2 and leading to the central office. Tapped onto one of the line wires 1 is a conductor 3 including in series a high efficiency transmitter 4.

5 designates a manually controlled three point switch comprising a blade 6 pivoted at one end upon a post 7, and contacts 8, 9 disposed at the opposite sides of the path of movement of the blade and adapted to be frictionally engaged thereby in the movement of the blade to circuit closing position. The free terminal of the conductor 3 is 55 tapped onto the contact 8, while leading from the contact 9 is a conductor 10 extend-

ing through the winding of an electro responsive device controlling the whistle 11 and connected with one side of a source of electrical energy as a battery 12. From the opposite side of the battery 12 leads a conductor 13 grounded upon one of the water pipes of the protected structure as at 14. A conductor 15 has one end connected with the pivot post 7 of the blade of the switch 5 and the opposite extremity grounded upon the pipe with the conductor 13.

In practice, should an intruder effect an entrance to the protected structure, the blade 6 is swung into engagement with the contacts 8 and 9 thereby connecting one side of the transmitter 4 with the earth and closing the circuit from the battery 12 through the electro responsive device controlling the whistle 11, current flowing from one side of the battery 12, through the conductor 10, the winding of the electro responsive device controlling the whistle 11, the contact 9, blade 6, pivot post 7, conductor 15, and then back to the other side of the battery 12 by way of the conductor 13. This switch blade 6, in the present instance, is manually controlled but it is to be understood that the same may be connected up with the various entrances to the protected structure in such manner that when one of such entrances is broken the blade will be swung to closed position. As the transmitter 4 is connected with the ground a signal is given at the central exchange whereby the operator's attention is attracted and as the operator connects the exchange set with the transmission line the sounds produced by the whistle 11 will be sent over the line from the receiver 4.

16 indicates a relay comprising, in the present instance, electro magnets 17 mounted upon a base 18, and a spring actuated armature 20 pivoted upon the upper end of a post 21 uprising from the base. Upstanding from the base adjacent to the free end 100 of the armature 20 is a standard 22 having the upper end thereof bent to provide a limb 23 disposed above the adjacent end of the armature and lying in parallelism therewith and fastened to the limb 23 and depending therefrom are contacts 24, 25 and 26 disposed in the path of movement of the armature 20 as the latter swings under the action of its spring. Leading from the contact 24 is a conductor 27 terminally connected with the conductor 3, while from the contact 25 leads a conductor 28 terminally

connected with the conductor 13. A conductor 29 is connected with the contact 26 and extends through a bell 30, the free terminal of the conductor 29 being tapped onto the conductor 10. The windings of the magnets 17 of the relay are connected in an electric circuit comprising a fusible wire 31 extending through the building or other structure to be protected, and a battery 32 connected in the fusible conductor.

In the event of the fusing of the wire 31, the flow of current through the windings of the magnets 17 of the relay 16 is interrupted whereby the spring of the armature 20 releases 15 and swings the latter into engagement with the contacts 24, 25 and 26 whereby the transmitter 4 is again connected with the line and the bell 30 energized, the conductor 3 being connected with the ground by way 20 of the conductor 27, contact point 24, contact point 25, conductor 28 and conductor 13, while current flows from one side of the battery 12, through the conductors 10 and 29 and the bell 30, the contact 26, conductor 25 28 and the portion of the conductor 13 back to the battery. Thus, the operator, upon "listening in" will hear the bell 30.

From the foregoing description taken in connection with the accompanying drawings, the construction and mode of operation of my improved signal system will be readily apparent. It will be seen that I have provided a signal system which may be used in conjunction with telephone lines 30 and whereby the central operator will be notified in the event of fire or burglary in the protected structure.

While I have herein shown and described one preferred form of my invention by way

of illustration, I wish it to be understood 40 that I do not limit or confine myself to the precise details of construction herein described and delineated, as modification and variation may be made within the scope of the claim without departing from the 45 spirit of the invention.

I claim:

In a signal system, the combination with a telephone transmission line, of an auxiliary transmitter having one terminal connected to one side of said line, a three point switch comprising two contacts and a switch blade movable into and out of engagement with said contacts simultaneously, a connection between the remaining terminal of said transmitter and one contact of said switch, a connection between the switch blade of said switch and the ground whereby when the blade is in closed position the circuit through the transmitter will be completed, 60 an audible signal having one terminal connected to the remaining contact of said switch, a source of energy having one side connected with the remaining terminal of said signal and the opposite side connected 65 to the connection between said switch blade and the ground whereby when the blade is in closed position the circuit through said audible signal will be closed and the audible signal sounded to send the sound waves 70 over said telephone transmission line by way of said auxiliary transmitter.

In testimony whereof I affix my signature in presence of two witnesses.

SIDNEY C. VENNERS.
